WINDOW FRAME HAVING REMOVABLE SASHES
Martin P. Clisham, 1105 Prospect Ridge Blvd.,
Haddon Heights, N.J.
Filed May 11, 1962, Ser. No. 193,916
3 Claims. (Cl. 20—12)

This invention relates to improvements in sliding sash window structures, and more particularly to a novel kit for converting the frames of such structures to provide for removal of the sashes without the use of tools.

The primary object of the invention is the provision of a kit of the kind indicated above, for either existing or new structures, which requires for its installation only the removal of the lower part of an existing sash guide, such as the inner guide, and its replacement with a removably mounted guide, grooving the lower part of the frame between the sashes to provide a seat for a spring-loaded guide, which is compressible out of the way to provide for removal of the upper sash, when in a lowered position, after removal of the lower sash, and forming seats for the flush mounting of retaining brackets for the removable guide. The installed kit renders removal and replacement of the window sashes from inside a building, so easy and simple that it can be performed by unskilled persons, without any tools, such as the average housewife, wishing to thoroughly clean and/or paint the sashes and the window frame, without subjecting herself to the labor and peril of having to use an outside ladder.

Another object of the invention is the provision of a simple kit of the character indicated above, which is composed of a small number of incomplex and easily formed metal parts, which can be made in well-finished and rugged forms, at relatively low cost, and whose components can be packed, stored, and shipped in compact, light-weight packages.

Other important objects and advantageous features of the invention will be apparent from the following description and the accompanying drawings, wherein, for purposes of illustration only, a specific form of the invention is set forth in detail.

In the drawings:

FIGURE 1 is an inside perspective view of a sliding sash window structure, with its lower sash broken away, showing removal of a lower part of the inner sash guide, preparatory to being replaced by a removable guide, and a spring-loaded center guide, in accordance with the present invention;

FIGURE 1^a is an exploded perspective view of a kit of the present invention;

FIGURE 2 is a fragmentary perspective view showing the spring-loaded center guide and the removable guide installed;

FIGURE 3 is an enlarged horizontal section taken on the line 3—3 of FIGURE 2;

FIGURE 4 is an elevation taken on the line 4—4 of FIGURE 3 with the sashes removed;

FIGURES 5 and 6 are further enlarged fragmentary vertical sections taken on the lines 5—5 and 6—6 of FIGURE 4;

FIGURE 7 is a fragmentary vertical section taken on the line 7—7 of FIGURE 6;

FIGURE 8 is a fragmentary vertical section taken on the line 8—8 of FIGURE 4.

2

Referring in detail to the drawings, wherein like numerals designate like parts throughout the several views, a conventional double sliding sash window frame 10 is shown, which has a vertical side member 12, which has, at its laterally inward side, an inside guide 14, a center guide strip 16, and an outside guide 18, with an upper sash 20 engaged between the outside guide 18 and the center guide strip 16, and a lower sash 22 engaged between the center guide strip 16 and the inside guide strip 14.

10 The frame side member 12 is prepared for the installation of the components of a kit of the present invention, by removal, in any suitable manner, of the lower part of the inside guide 14, to a height slightly greater than the height of either of the sashes 20 and 22, so as to provide a plane flat surface 24, the removal of an equal length of the center guide strip 16, and the formation of a vertical groove 26, in the area of the side member 12 left by removed part of the center guide strip 16.

15 The illustrated kit, generally designated 28, comprises a spring-loaded center guide assembly 30, a removable inside guide 32, and reversed upper and lower locking brackets 34 and 36, respectively, which are vertically spaced from each other at a greater distance than the height of the sashes 20 and 22. These components are 20 preferably made of non-corrosive, light-weight metal, such as aluminum.

The spring-loaded center guide assembly 30 comprises a relatively deep and narrow channel 38 having full 25 length, lateral flanges 40, at its open inner side, formed with screw holes 42 for the reception of mounting screws 44. The web 46 of the channel 38 has openings 48, adjacent its upper and lower ends, through which slide vertically spaced carrier pins 50, having heads 52, on their 30 laterally outward ends, which bear against the laterally outward side of the web. The pins 50 have coil springs 54 circumposed thereon, and compressed between the web 46 and the adjacent edge of a vertically elongated bar 56 which is engaged slidably in the open end of the channel 38 and normally projects inwardly therefrom. The pins 50 are threaded or otherwise secured to the outward edge of the bar 56. The channel 38 is secured in place in the groove 26 by threading the screws 44 through the flange 35 openings 42 into the frame side member 12, the upper and lower ends of the channel 38 preferably abutting the shoulder 58, at the upper end of the groove 26, and the window sill 60, respectively.

The removable inside guide 32 comprises a laterally outwardly opening flat channel 62 having spaced and opposed inwardly extending flanges 64, on its open end. The web 66 of the channel 62 is formed, adjacent its upper end, with a vertically elongated slot 68, and spaced below the slot is a lateral horizontal web 70, which is 40 preferably fixed to the flanges 64 and to the sidewalls 72 of the channel.

The horizontal web 70 is formed centrally with a hole 74 through which works a vertical latch bolt 76, having a head 78, on its lower end, which normally bears against the underside of the web 70. The bolt 76 has a reduced upper end portion 80 which extends upwardly through a bore 82 provided in a slide 84, which extends across the 45 interior of the channel 62 and bears against the channel web 66, the sidewalls 72, and the flanges 64. A conical detent 86 is fixed on the upper end of the bolt 76, atop the slide and a coil spring 88, circumposed on the lower 50

part of the bolt, is compressed between the web 70 and the underside of the slide 84 and normally elevates the detent 86, into a hole 90, provided in the foot portion 92 of an upper L-shaped locking bracket 34, which has an upstanding standard 96, which is secured to the surface 24 of the frame side member 12, by screws 98.

The channel 62 has therein a lower horizontal web 100, adjacent to its lower end, which has a central bore 102, in which is engaged the upstanding shank 104 of a downwardly directed conical detent 106, the shank being riveted, at its upper end, as indicated at 103, against the top of the web 100. A lower inverted L-shaped locking bracket 36 has its standard portion 112 secured to the surface 24, as by means of screws, and its foot portion 114 is provided with a hole 116, in which the detent 106 engages. The channels 38 and 62 are preferably of the same length and somewhat longer than the window sashes.

Removal from the window frame 10 of the lower sash 22, is accomplished simply by depressing the upper detent 86, by means of a knob 118 on a shank 120, extending through the slot 68 and threaded into the slide 84, against the resistance of the spring 88, so as to disengage the detent 86 from the bracket hole 90, and then elevating the channel 62, so as to disengage the lower detent 106 from the hole 116 of the lower bracket 36, and then moving the lower sash 22 toward the inside and out of the frame 10.

The upper sash 20 is removed by first lowering the same to its bottom position, then pressing the bar 56 outwardly against the resistance of the springs 54, far enough to enable the upper sash to be moved toward the inside of and out of the window frame. These operations are reversed for replacing the sashes 20 and 22 in the window frame.

Although there has been shown and described a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. In combination, a window frame having a sill, an upstanding side member having spaced vertical inside and outside guides and a center guide strip between the guides, an upper slide sash engaged between the outer guide and the center guide strip, a lower slide sash engaged between the center guide strip and the inside guide, the center guide strip extending from the upper end of the frame to and terminating at a point spaced above the lower end of the frame with the part between the terminating point of said center guide strip and the lower end of said frame forming a vertical groove, the inside guide extending from the upper end of the frame to and terminating at a point spaced above the lower end thereof with the part between the terminating point of said inside guide and the lower end thereof providing a flat surface, a spring-loaded center guide secured in said groove and having an inwardly spring-pressed guide bar extending inwardly from the frame side member and engaging the inside surface of the upper sash, and a removable inside guide engaged with and removably secured to said flat surface, said center guide and said inside guide being taller than the heights of the individual sashes, said spring-loaded center guide comprising an inwardly opening channel secured in said groove, a vertically elongated bar engaged in and normally reaching inwardly beyond the channel, means mounting the bar to move inwardly and outwardly in the channel, and spring means compressed between the channel and the bar, said channel having a web, said mounting means comprising headed pins sliding through the channel web and secured to the bar.

2. In combination, a window frame having a sill, an upstanding side member having spaced vertical inside

and outside guides and a center guide strip between the guides, an upper slide sash engaged between the outer guide and the center guide strip, a lower slide sash engaged between the center guide strip and the inside guide, the center guide strip extending from the upper end of the frame to and terminating at a point spaced above the lower end of the frame with the part between the terminating point of said center guide strip and the lower end of said frame forming a vertical groove, the inside guide extending from the upper end of the frame to and terminating at a point spaced above the lower end thereof with the part between the terminating point of said inside guide and the lower end thereof providing a flat surface, a spring-loaded center guide secured in said groove and having an inwardly spring-pressed guide bar extending inwardly from the frame side member and engaging the inside surface of the upper sash, and a removable inside guide engaged with and removably secured to said flat surface, said center guide and said inside guide being taller than the heights of the individual sashes, said spring-loaded center guide comprising an inwardly opening channel secured in said groove, a vertically elongated bar engaged in and normally reaching inwardly beyond the channel, means mounting the bar to move inwardly and outwardly in the channel, and spring means compressed between the channel and the bar, said channel having a web, said mounting means comprising headed pins sliding through the channel web and secured to the bar, said inside guide comprising an outwardly opening channel having its open side secured to said flat surface, and releasable locking means comprising vertically spaced upper and lower brackets fixed to said flat surface and having detent

3. In combination, a window frame having a sill, an upstanding side member having spaced vertical inside and outside guides and a center guide strip between the guides, an upper slide sash engaged between the outer guide and the center guide strip, a lower slide sash engaged between the center guide strip and the inside guide, the center guide strip extending from the upper end of the frame to and terminating at a point spaced above the lower end of the frame with the part between the terminating point of said center guide strip and the lower end of said frame forming a vertical groove, the inside guide extending from the upper end of the frame to and terminating at a point spaced above the lower end thereof with the part between the terminating point of said inside guide and the lower end thereof providing a flat surface, a spring-loaded center guide secured in said groove and having an inwardly spring-pressed guide bar extending inwardly from the frame side member and engaging the inside surface of the upper sash, and a removable inside guide engaged with and removably secured to said flat surface, said center guide and said inside guide being taller than the heights of the individual sashes, said spring-loaded center guide comprising an inwardly opening channel secured in said groove, a vertically elongated bar engaged in and normally reaching inwardly beyond the channel, means mounting the bar to move inwardly and outwardly in the channel, and spring means compressed between the channel and the bar, said channel having a web, said mounting means comprising headed pins sliding through the channel web and secured to the bar, said inside guide comprising an outwardly opening channel having its open side secured to said flat surface, and releasable locking means comprising vertically spaced upper and lower brackets fixed to said flat surface and having detent

openings, a fixed lower detent on the inside guide channel engaging downwardly in the detent opening of the lower bracket, an upwardly spring-pressed detent in the inside guide channel releasably engaged in the detent opening of the upper bracket, and externally accessible means 5 guided on the inside guide channel and connected to the spring-pressed detent for depressing the spring-pressed detent out of the detent opening of the upper bracket, said detents and said brackets being located within the channel of the inside guide.
